TUBE DISPENSER WITH CASING

Florence M. Brown, Chippewa Lake, Ohio

Application May 11, 1948, Serial No. 26,371

2 Claims. (Cl. 222—100)

1

This invention relates to means for dispensing or discharging the contents of flexible tubes such as are commonly employed for the purpose of containing toothpaste, shaving cream, or the like. My invention more particularly comprises novel and improved means to engage the end of the tube remote from the discharge end for cooperation with the tube to effect progressive squeezing action for dispensing the contents therefrom; and my invention additionally embodies improved means for suspending the dispenser device from a wall or other supporting structure.

In prior tube dispensers of the type to which my invention relates there have usually been provided means for engaging the end of the tube remote from the discharge end thereof for winding up the tube to effect progressive squeezing action to effect discharge of the contents thereof. Such means as heretofore proposed have been in the form of a slotted key or the like designed so that the non-discharge end of the tube may be received in the slotted portion of such key so that rotation of the latter operates to gradually wind the tube about the key beginning with the non-discharge end and progressing in the winding action toward the discharge end of the tube.

Such constructions as heretofore proposed have necessitated that when the tube is completely wound about the key down to the discharge end of the tube, the portion of the tube wound about the key has to be unwound therefrom in order to enable removal of the tube from the key to permit engagement thereof with a fresh tube filled with the material to be dispensed. This necessity to unwind the tube from the actuating key in order to remove therefrom the used tube from which the contents have been discharged constitutes an inconvenience and annoyance to the user and is an unpleasant task due to the fact that the winding of the tube upon the key crushes and fractures the same, squeezing out portions of the contents which spread over the coiled portions of the tube and is sticky and otherwise disagreeable in condition when the time comes for unwinding the tube from the key for removal thereof. This makes the handling of the tube for unwinding quite disagreeable.

It is a principal object of my invention to provide improved means engageable with the tube and operable to wind or coil the discharged portion of the tube thereabout, which means is readily disengageable from the tube coiled about the same without unwinding of the tube therefrom.

For the accomplishment of this objective, my in-

2

vention contemplates the provision of a spool or reel structure comprising detachably cooperable parts operable to provide an efficient reel for winding of the tube thereon and readily disengageable from the coiled portion of the tube without unwinding of the same.

Other features of my invention involve the cooperation of the parts of the reel structure for rigid axial alignment thereof under normal operating conditions, and the provision of guiding means cooperable with the housing of the dispenser device for maintaining transverse alignment of the spool or reel structure in reference to the said housing during longitudinal movement of the spool or reel structure relative to the housing in reference to the progressive longitudinal movement of the spool or reel structure toward the discharge end of the tube disposed at the discharge end of the housing.

Reference is now made to the accompanying drawings, in which:

Figure 1 is a rear elevation of a tube dispenser embodying the invention.

Figure 2 is a vertical sectional view of the same.

Figure 3 is a horizontal sectional view of the same.

Figure 4 is a view showing one of the cooperating parts of the novel spool or reel structure alone.

Figure 5 is a view showing the other of said cooperating parts of the said spool or reel structure alone.

Figure 6 is a view of the spool or reel structure with the cooperating parts shown in their cooperative relation.

Referring to the drawings and describing the invention in detail, the numeral 1 generally indicates a tube dispenser embodying my invention and comprising a rectangular housing 2 for enclosing a tube 3 containing toothpaste, shaving cream, or the like, said housing 2 having a closed bottom end 4 provided with an aperture through which extends the neck 5 of the tube 3, which neck 5 threadedly receives the usual screw cap 6. The upper end of the housing 2 detachably receives a removable cap 7.

Each side 2a and 2b of the housing 2 is provided with a respective vertical longitudinal slot 8 as seen best in Figures 2 and 3, the said slots 8 both extending from the upper edge of the housing 2 substantially to the lower end thereof and serving to receive the guide portions of the reel or spool structure for guiding the latter in its longitudinal movement relative to the housing 2 as the tube 3 is wound or coiled thereupon.

The spool or reel structure comprises the de-

tachably cooperable parts respectively designated by the numerals 9 and 10, as best seen in Figures 4 and 5, the members 9 and 10 being substantially identical in form and comprising the hollow stem or reel portions 11 and 12, respectively, which are cylindrical in outer configuration and are provided with aligned axial slots extending from one end almost the entire axial length thereof. The aligned axial slots provided in the stem or reel portion 11 of the member 9 are indicated by the numeral 13 and the corresponding aligned axial slots of the stem or reel portion 12 of the member 10 are indicated by the numeral 14.

The outer cylindrical diameter of the stem or reel portion 11 is just slightly smaller than the inner diameter of the corresponding portion 12 of the member 10, so that the portion 11 of the member 9 may be received within the portion 12 of the member 10 as shown in Figure 6. When so received, the members 9 and 10 are coaxially related and may be rotated relatively to one another to align the slots 13 with the slots 14 so that the closed end of the tube 3 remote from the discharge end may be inserted through the aligned slots 13 and 14 of the assembled spool or reel structure generally designated by the numeral 15 and comprising the parts 9 and 10. Or, if desired, the closed end of the tube or the portion of the tube adjacent thereto may be slid through the open end of the slots 13 or 14 axially of the respective member 9 or 10 and then the other of said members may be disposed in cooperative relation with the first of said members, whereby the portion 11 of the member 9 is received within the portion 12 of the member 10 with the slots 13 and 14 aligned and the portion of the tube extending therethrough.

It will be noted that the member 9 is provided with a hand engaging knob 15 and the member 10 is provided with a similar knob 16. Each of the members 9 and 10 is provided with an annular groove intermediate the knob 15 and the respective stem or reel portion, the annular groove of the member 9 being indicated at 17 and the corresponding annular groove of the member 10 being indicated at 18.

With the spool or reel parts 9 and 10 assembled as above described in conjunction with the end portion of the tube 3, the cap 7 is removed from the housing 2 and the tube 3 inserted neck end down so that the neck part extends through the aperture in the lower end 4 of the housing 2. The grooved portions 17 and 18 of the spool or reel structure are inserted in the respective slots 8 at either side of the housing 2 so that the spool or reel structure 20 is aligned transversely of the housing and guided for vertical longitudinal movement by engagement of the slot edges of the housing in the grooves 17 and 18. The cap 1 being replaced upon the housing 2, the tube dispenser 1 may be hung in any convenient place on a wall or cabinet by virtue of the provision of the keyhole slot 19 in the rear side of the housing 2. Thus the tube dispenser 1 may be hung on a nail in the wall or cabinet, the head of the nail extending from the wall being caused to be inserted through the large portion of the keyhole slot and the shank of the nail entering the narrow portion of the keyhole slot when the device is in place for suspension by the nail.

The operation of dispensing the contents of the tube 3 from the device will be readily understood. The cap 6 is removed from the tube and then the knob 9 or 10 is rotated to thereby ro-

tate the spool or reel structure to wind or coil thereupon the end of the tube engaged thereby, resulting in a progressive squeezing action being applied to the tube to cause the contents thereof to be forced outwardly for discharge through the neck 5 of the tube.

After a period when the continued winding up of the tube 3 has coiled on the spool or reel structure substantially the entire tube, completing the discharge of the contents thereof, the operation of removing the coiled up tube from the spool or reel structure is very simple. The cap 7 being removed from the housing and the cap 6 being removed from the tube 3, if the device is disposed with its open end downwardly, the reel or spool and its coiled up tube 3 will drop out, the reel structure sliding down the slots 8. Thereupon the knobs 15 and 16 may be engaged and moved relatively away from one another to separate the parts 9 and 10 and disengage the same from the empty tube 3. This eliminates the necessity for unwinding the coiled up tube 3, and if the reel structure is held over a wastebasket when the latter operation is being performed, a separation of the parts 9 and 10 will enable the same to be slipped off the tube 3 and the latter dropped into the wastebasket without touching the hands of the user, to thereby avoid soiling the hands by contact with the extruded sticky contents of the tube which may have become squeezed onto the exterior thereof in the use of the tube dispenser.

In Figure 6 the reel or spool device is shown in assembled condition with the detachably cooperable stem parts 9 and 10 in their cooperative coaxially aligned relation, as when the portion 11 is telescopically fitted within the portion 12. Since the aligned axial slots 13 are open at their ends, as at 13a, and the corresponding slots 14 are similarly open at their ends, as at 14a, it is readily seen that alignment of the slots 13 and 14, when the portions 11 and 12 are in telescoping relation, serves to provide practically a single continuous slot through the central portion of the reel 20 through which a portion of the flexible tube 3 may extend.

Figure 2 best shows the alignment of the axial slots 13 with the axial slots 14 and how, under such condition of assembled relation of the parts 9 and 10, a portion of the tube 3 extends through the central portion of the reel 20, as above described. It may be noted from Figure 2 that while the slots 13 are wide enough to receive the empty flattened portion 3a of the tube 3, said slots 13 are narrower than the thickened reinforced end portion 3b of the tube so that the latter portion serves as an abutment engaging the periphery of the stem portion 11 to prevent the end of the tube from being pulled through and thereby disengaged from the reel during the initial stage of the operation of winding the tube 3 upon the reel.

Having thus described my invention, what I claim as new and desire to secure by Letters Patent of the United States, is:

1. A tube dispenser of the class described, comprising a housing for a tube to be dispensed, a reel device comprising detachably cooperable reel stem parts cooperable for axial alignment, said stem parts each having aligned open ended slots therein alignable to form a single continuous slot extending axially of the reel for receiving therein a portion of a flexible tube to be coiled thereon, and cooperating guide means on said reel device and said housing to mount the reel device on said housing for rotation and for movement relative to the housing in the plane of the rotational axis

of the reel device in guided relation to the housing transversely thereof, said stem parts being of hollow cylindrical formation, the open end of the slotted portion of one of said stem parts telescopically fitting within the corresponding portion of the other stem part.

2. A tube dispenser of the class described, comprising a housing for a tube to be dispensed, having aligned guide slots at opposite sides thereof, a reel device comprising detachably cooperable reel stem parts cooperable for coaxial alignment, said stem parts being of hollow cylindrical formation, each stem part having open ended slots therein aligned in the plane of the reel axis, the open end of the slotted portion of one of said stem parts telescopically fitting within the corresponding portion of the other stem part, said stem parts when in said telescopic relation being relatively rotatable for alignment of the slots of both stem parts in the plane of the reel axis to form a single continuous slot extending through the reel and

5 10 15 20

axially thereof and through which a portion of a flexible tube to be coiled on the reel device may be inserted, and each of said stem parts having an annular groove engageable with a respective one of said guide slots to mount the reel device on said housing for rotation and for movement relative to the housing in the plane of the rotational axis of the reel device in guided relation to the housing transversely thereof.
